(57) **CLAIM**

We claim the ornamental design for a surface-roughness measuring probe, as shown and described.

DESCRIPTION

FIG. 1 is a front perspective view of a surface-roughness measuring probe, showing our new design;

FIG. 2 is a rear perspective view thereof;

FIG. 3 is a front view thereof, the rear view being a mirror image thereof;

FIG. 4 is a left-side view thereof;

FIG. 5 is a right-side view thereof;

FIG. 6 is a top view thereof; and,

FIG. 7 is a bottom view thereof.
